AIR CONDITIONING APPARATUS

Milton Kalischer, Springfield, Mass., assignor to
Westinghouse Electric & Manufacturing Com-
pany, East Pittsburgh, Pa., a corporation of
Pennsylvania

Application December 13, 1938, Serial No. 245,497

5 Claims. (Cl. 62—140)

My invention relates to air conditioning apparatus, more particularly to an air cooled, self-contained room cooler adapted to be disposed in the room to be cooled and to communicate with outdoors through a window in a wall of the room.

The invention has for an object to provide an improved room cooler of the character set forth.

A further object is to provide an improved arrangement of condenser and air stream for cooling the same.

Another object is to provide an improved arrangement for evaporating condensate in the condenser air stream.

These and other objects are effected by my invention as will be apparent from the following description and claims taken in accordance with the accompanying drawings, forming a part of this application, in which:

Fig. 1 is a perspective view of a room cooler, with parts broken away;

Fig. 2 is a side elevation thereof; and

Fig. 3 is a horizontal sectional view.

Referring to the drawings in detail, I show a unit room cooler including a vertical portion 10 and a horizontal projecting portion 11 which projects rearwardly from the upper part of the vertical portion.

The room cooler includes a unitary frame 12 of any suitable construction for both the vertical and projecting portions, and a cabinet 13 enclosing the same. The room cooler is adapted to be mounted in the window of the room to be cooled, the projecting portion 11 being projected through the window and resting on the window sill while the lower part of the vertical portion bears against the wall below the window.

An evaporator 14 is mounted on the frame 12 in the upper part of the vertical portion and a drain pan 15 is mounted beneath the evaporator for collecting the moisture condensed from the air by the evaporator. An enclosed motor compressor unit 16 is mounted on the frame 12 in the lower part of the vertical portion and is preferably enclosed in a sound-absorbing box or enclosure 17. The cabinet is formed with air inlets 18 in the sides of the vertical portion and an outlet 19 in the top thereof. Air filters 21 may be disposed against the inlets 18.

A fan 22 is disposed above the evaporator and operates to effect flow of air inwardly through the inlets 18 and the filters 21, then upwardly between the box 17 and the cabinet, over the edge of the drain pan 15 to the underside of the evaporator 14, then upwardly over the surfaces

of the evaporator, through a cloth duct member 23 and a fan shroud 24 to the outlet 19, from which it is discharged into the room. A float valve 25 and an accumulator 26 are disposed adjacent the end of the evaporator, as shown.

The vertical portion of the illustrated room cooler is generally similar, with the exception of the condenser, to the room cooler shown and described in the application of R. E. Holmes, Serial No. 113,557.

A condenser 27 is disposed in the projecting portion adjacent the outer side thereof, as shown on the drawings. The condenser may be of any suitable construction. In the illustrated embodiment it is of the cross-finned type, comprising tubes and blades or fins extending transversely of the tubes. A pan 28 is mounted at the bottom of the projecting portion between the vertical portion 10 and the condenser 27. A tube 29, arranged as shown in Fig. 2, conveys the condensate from the drain pan 15 to the pan 28 to be evaporated therein.

A fan 31 is provided for effecting flow of outdoor air over the condenser to cool the same and over the pan 28 to evaporate the condensate therein. The fan 31 is disposed in a fan opening formed in a partition 32 which extends inwardly from an intermediate point of the condenser to the vertical portion 10. The fan 31 is overhung on the shaft of a drive motor 33 which is suspended from a removable inner cover plate 34 by a bracket 35. The fan effects flow of air inwardly over one-half of the condenser, then over one-half of the pan 28 and over the motor 33 to the fan 31, then from the fan over the other half of the pan 28 and over the other half of the condenser to outdoors.

Tubing 36, which may be bent to serpentine form as shown, is placed in the pan 28. Compressed refrigerant gas which is discharged from the compressor at high temperature is conveyed through the tubing 36 before being admitted to the condenser and supplies heat to the condensate in the pan 28 to facilitate its evaporation.

The compressor, the condenser, and the evaporator are connected in refrigerant flow relation. Refrigerant is compressed by the motor compressor unit and discharged therefrom at high temperature. It is conveyed through connecting tubing 37 to the tubing 36 in the pan 28, where it gives up some of its heat, mostly its superheat, to the condensate in the pan. This heat transfer serves two purposes, first, it effects some of the heat removal from the refrigerant, and, secondly, it supplies latent heat of vaporiza-

zation to the condensate to facilitate its evaporation in the air stream flowing over the same.

The partially cooled refrigerant gas is then conveyed through a connecting conduit 38 to the inlet header 38 of the condenser 27, wherein the refrigerant is condensed. The condensed refrigerant is discharged from the outlet header 41 of the condenser to a conduit 42 by which it is conveyed to the float valve 25. The latter controls the admission of refrigerant to the evaporator 14, wherein it is vaporized by the heat extracted from the air flowing over the evaporator. The vaporized refrigerant flows through a conduit 43, the accumulator 26, and a conduit 44 to the motor compressor unit 16.

As the air is drawn over one portion of the condenser, its temperature is raised by the heat extracted therefrom, thereby increasing the moisture-carrying capacity of the air. Thus, as the air flows over the pan 28, it serves to evaporate the condensate contained therein. The contact of the air with the condensate also serves to cool the air, due to the fact that the condensate absorbs heat from the air to effect vaporization thereof. Accordingly, the air being at reduced temperature is more effective to cool the second half of the condenser as it passes over the same to outdoors.

The condenser fan 31 may be located, as shown in Fig. 2, so that if the liquid in the pan 28 rises 30 abnormally high, the blade tips of the fan will dip into the liquid and splash it against the condenser 27.

Provision may be made for changing the air in the room. For example, as shown in Fig. 3, an opening 45 controlled by a damper 46 may be provided in the wall 47 between the evaporator compartment 48 and the condenser compartment 49. When the damper 46 is in open position, room air which has entered through the inlets 18 and the filters 21 is withdrawn from the evaporator compartment 48 before it passes over the evaporator 14. This air passes into the condenser chamber 49 on the suction side of the fan 31 and is then forced along with the outdoor air over the remaining half of the pan 28 and condenser 27 and discharged to outdoors. The air withdrawn from the room is replaced by outdoor air, thereby providing for ventilation of the room.

While I have shown my invention in but one form, it will be obvious to those skilled in the art that it is not so limited but is susceptible of various changes and modifications without departing from the spirit thereof, and I desire, therefore, that only such limitations shall be placed thereupon as are imposed by the prior art or as are specifically set forth in the appended claims.

What I claim is:

1. A self-contained room cooler comprising frame and housing structure, a condenser, an evaporator, means for conveying air over said evaporator and delivering the same to the room to be cooled, a drain pan disposed beneath said evaporator to collect condensate formed thereon, a second pan, means for conveying condensate from said drain pan to said second pan, means for conveying hot refrigerant gas discharged from said compressor in heat transfer relation to the condensate in said second pan to provide heat for evaporation thereof and thence to said condenser, and means including a fan for effecting flow of a stream of cooling air over one portion of said condenser, then over said pan to evaporate condensate therein and thence over a second portion of said condenser.

2. A self-contained room cooler adapted to be disposed in a room having a window in a wall thereof, said room cooler comprising a vertically extending portion adapted to be disposed in said room adjacent said wall and a second portion projecting horizontally through the window from the upper portion of said vertical portion, an evaporator and a compressor in said vertical portion, a condenser disposed in said projecting portion adjacent the outer side thereof, a drain pan disposed in said projecting portion inwardly of said condenser, means for conveying condensate from said evaporator to said drain pan, means for conveying hot refrigerant gas discharged from said compressor in heat transfer relation to the condensate in said pan and thence to said condenser, and means including a fan disposed inwardly of said condenser for conveying air inwardly from one portion of the condenser, over said pan to evaporate condensate therein and then outwardly through another portion of said condenser.

3. A self-contained room cooler adapted to be disposed in and to cool a room having a window in a wall thereof, said room cooler comprising a vertically extending portion adapted to be disposed in said room adjacent said wall and a second portion projecting horizontally through the window from the upper portion of said vertical portion, an evaporator and a compressor in said vertical portion, a condenser disposed in said projecting portion adjacent the outer side thereof, a pan disposed in said projecting portion inwardly of said condenser, means for conveying condensate from said evaporator to said pan, and means including a fan disposed inwardly of said condenser for effecting flow of air inwardly through one portion of said condenser, over said pan to evaporate condensate therein and outwardly through another portion of said condenser, said pan having upturned flanges to retain condensate therein and having a substantial area disposed inwardly of the condenser and along both said portions thereof so that the air flowing between said condenser portions contacts the surface of the condensate in the pan to effect said evaporation.

4. A self-contained room cooler adapted to be disposed in a room having a window in a wall thereof, said room cooler comprising a vertically extending portion adapted to be disposed in said room adjacent said wall and a second portion projecting horizontally through the window from the upper portion of said vertical portion, an evaporator and a compressor in said vertical portion, a condenser disposed in said projecting portion adjacent the outer side thereof, a pan disposed in said projecting portion inwardly of said condenser, means for conveying condensate from said evaporator to said pan, and means, including a partition extending inwardly from an intermediate point of said condenser and having a fan opening therein and including a fan in said opening, for conveying air inwardly from one portion of the condenser, over said pan to evaporate condensate therein and through said opening, and then outwardly through another portion of said condenser.

5. A self-contained air cooling unit having a horizontally-extending portion adapted to be disposed in a window opening of a room and including a compressor, an evaporator disposed adjacent the inner side of the unit, a condenser mounted vertically along the outer side of said horizontally-extending portion and parallel to

the window, a pan disposed at substantially the level of the bottom of said condenser and extending inwardly therefrom, said pan receiving and retaining the condensate formed on said evaporator, a fan disposed directly above said pan for effecting flow of air inwardly through one portion of said condenser, over said pan in contact with

the condensate therein and outwardly over a second portion of said condenser, the arrangement being such that the air stream flowing between said one and said second condenser portion is disposed substantially entirely above the bottom of said pan.

MILTON KALISCHER.
